UNITED STATES PATENT OFFICE

PATRICK F. KING, OF NEW BRITAIN, CONNECTICUT, ASSIGNOR TO THE STANLEY WORKS,
OF NEW BRITAIN, CONNECTICUT, A CORPORATION OF CONNECTICUT

SLIDING DOOR ARRANGEMENT

Application filed February 9, 1931. Serial No. 514,426.

This invention relates to the art of doors, and is more particularly concerned with structures of the type wherein the doors are supported for sliding movement. As an instance of a use to which the present invention may be applied, reference may be had to aircraft hangars and other similar structures, and to which use the improvements of the present invention are peculiarly adaptable, although not strictly limited thereto.

It is the usual practice in aircraft hangar structures to employ a plurality of sliding doors of comparatively large dimensions and massive weight and to mount the several doors on separate tracks, the tracks extending across the doorway and being positioned one behind the other. This practice is open to numerous objections and disadvantages, among which may be mentioned the relatively large amount of space occupied by the tracks and which space, as far as housing of the aircraft is concerned, is practically wasted. In some cases, the distance between the front and the rear tracks is as great as three feet. The laying of a plurality of tracks and the installation of corresponding overhead tracks entail relatively large expense for the materials employed and also for the construction work.

The present invention has as its object the provision of an improved construction wherein the number of tracks within the hangar doorway is reduced to a minimum, and the doors may be brought into position one behind the other at one side of the hangar without increasing the width of the doorway or the extent to which the doors, when in open position, extend beyond the side of the hangar. To these ends, there is provided, in accordance with the present invention, a single supporting track within the doorway adapted to hold a number of doors end to end, and at one end of the supporting track is a carrier adapted to be moved to successive positions so as to receive the doors in a relation one behind the other. My improved construction is a very simple one wherein the doors may be very easily and conveniently moved to shut or open

positions as desired, and the space occupied by the doors within the hangar opening is relatively small. My improved arrangement may be installed at a lesser cost than the arrangements now generally employed. 55

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims. 65

In the accompanying drawings, the improvements of the present invention are shown more or less diagrammatically as being incorporated in an aircraft hangar, only so much of the latter being illustrated 70 as is necessary for a complete understanding of the invention.

In these drawings, Fig. 1 is a front elevational view of one end of the hangar, and illustrates two doors as being supported by the track in the hangar doorway, and one door as having been moved to complete open position;

Fig. 2 is an elevational view looking at one side of the truck or carriage onto which 80 three of the doors have been slid; and

Fig. 3 is a top plan view of what is shown in Fig. 2.

Referring to the drawings in detail, 9 designates one side wall of the hangar; 10, 85 the roof; and 11, the concrete floor thereof. The numerals 12, 13, and 14 designate the several doors mounted on rollers or wheels 15 of any suitable number. These rollers are more or less diagrammatically illustrated as the construction thereof forms no part of the present invention. Rollers of this type are old and well known in the art. Each door may have at its top edge suitable horizontally disposed rollers 16. 90

Embedded in the floor 11 of the hangar and in the doorway thereof is a supporting track 20, which may be of the usual I-beam construction and which is of such length as to support a plurality of doors, end to end. 100

Positioned at the top of the doorway and in vertical alignment with the supporting track 20 is an overhead track 21 which may be of the usual box type. This track is adapted to receive the overhead rollers 16 in such manner that the rollers engage the vertical walls of the track at diametrically opposite points.

To one side of the hangar is a concrete foundation 25, the upper surface of which 10 is below the surface of the floor 11, and embedded in this foundation are two spaced apart parallel tracks 26 which are disposed at an angle to the track 20. In the present instance, the tracks 26 are at right angles to 15 the track 20, and they run rearwardly along the side of the hangar. At the forward and rear ends of the tracks 26 are suitable stops or buffers 27. Mounted upon the tracks 26 is a truck or carriage of any suitable construction. By preference, the frame of the truck is of skeleton frame, the frame members being designated by the numerals 28. The truck, at opposite sides, has pairs of 20 wheels 29, respectively riding on the tracks 25 26. Mounted on and extending transversely of the truck is a plurality of supporting tracks 30 of a construction identical to the track 20 and located at the same height as the track 20. These tracks 30 are positioned 30 one behind the other in parallel arrangement so that, by moving the truck, they may be brought successively into alignment with the track 20. In the upper portion of the truck is a plurality of overhead tracks 31, 35 vertically aligned with the respective tracks 30, and of like construction as the overhead track 21. These tracks 31 are so positioned that they may be brought successively into exact alignment with the overhead track 21.

40 Any suitable means may be employed for moving the truck to its several positions so as to receive and deliver the doors. For example, one of the bottom side sills of the truck may have a rack 35 with which meshes 45 a pinion 36 fixed to a shaft 37 mounted in suitable fixed bearings 38. This shaft may extend through the side wall 9 of the hangar. On the other end of the shaft 37 is a suitable ratchet wheel 39 with which cooperates 50 a pawl 40 operatively associated with a lever 41. By moving the lever 41 back and forth, the shaft 37 is turned in one direction or the other, as the case may be, so as to move the truck. There may be provided, at the 55 top of the truck and above the overhead tracks 31, a suitable shroud or canopy 42 for protecting the tracks against rain and snow. This canopy is shown in Fig. 2 but is omitted from the other figures.

60 The operation of my improved arrangement will be clear from the foregoing description taken in connection with the accompanying drawings. It will be observed that, when the hangar is closed, all of the doors 65 are positioned on the track 20 in end to end

relation. When it is desired to open the hangar, the endmost door is slid onto one of the tracks 30 of the truck; then the truck is moved to bring another track 30 into alignment with the track 20, and the second door is moved onto the truck, and so on until all of the doors have been moved onto the truck. To close the hangar door, the operation is 70 reversed.

As many changes could be made in the 75 above construction and many apparently widely different embodiments of this invention could be made without departing from the scope thereof, it is intended that all matter contained in the above description or shown in the accompanying drawings shall be interpreted as illustrative and not in a limiting sense.

80 It is also to be understood that the language used in the following claims is intended to cover all of the generic and specific features of the invention herein described and all statements of the scope of the invention which, as a matter of language, might be said to fall therebetween.

90 What is claimed is:

1. A door arrangement for aircraft 95 hangars and the like, comprising a supporting track adapted to receive a plurality of doors in end to end relation, a truck located at one end of said track and movable at an angle thereto, and a plurality of tracks on said truck one behind the other and adapted to be respectively brought into registry with said first mentioned track.

2. A door arrangement for aircraft 100 hangars and the like, comprising a track adapted to receive a plurality of doors in end to end relation, a truck located at one end of said track and movable at an angle thereto, said truck having a plurality of tracks one behind the other and each of such length as to support a single door, said last mentioned tracks being arranged to be respectively brought into alignment with said first mentioned track.

3. A door arrangement for aircraft 105 hangars and the like, comprising a supporting track and an overhead track in vertical alignment therewith, a plurality of doors adapted to rest on said supporting track and to be guided at their upper ends by said overhead track, and a truck at one end of said tracks and having a plurality of supporting tracks one behind the other at substantially the same level as said first supporting track, said truck also having a plurality of overhead tracks respectively associated with said supporting tracks and adapted to be respectively brought into alignment with said first mentioned overhead track, and means for supporting said truck for movement at right angles to said tracks.

4. A door arrangement for aircraft 115

hangars and the like, comprising a structure having a doorway provided with a supporting track and an overhead track, a truck located at one side of said structure and having a plurality of tracks one behind the other and substantially at the same level as said first mentioned supporting track, said truck also having overhead tracks respectively associated with said supporting tracks and 10 adapted to be brought into alignment with said first mentioned overhead track, and means for supporting said truck for movement at right angles to said tracks.

5. A door arrangement for aircraft 15 hangars and the like, comprising a structure having a floor and a doorway, a track on said floor and located in said doorway and adapted to receive a plurality of doors, an overhead track in said doorway, a plurality 20 of doors adapted to ride on said supporting track and to be guided by said overhead track in end to end relation, a pair of truck tracks at right angles to at one end of, and on the level below said supporting track, a 25 truck provided with wheels engaging on said last mentioned tracks, relatively short tracks on said truck extending in the same direction as and located at the same level as said first mentioned supporting track, said short 30 tracks being positioned one behind the other and each adapted to receive a single door, and a plurality of overhead tracks on said truck respectively associated with said short tracks and adapted to be brought into linear 35 alignment with said first mentioned overhead track.

6. A door arrangement for aircraft 40 hangars and the like, comprising a supporting track adapted to receive a plurality of doors in end to end relation, a truck located at one end of said track and movable at an angle thereto, a plurality of tracks on said truck one behind the other and adapted to be respectively brought into registry with said 45 first mentioned track, and means for moving said truck.

7. A door arrangement for aircraft 50 hangars and the like, comprising a structure having a doorway provided with a supporting track and an overhead track, a truck located at one side of said structure and having a plurality of tracks one behind the other and substantially at the same level as said first mentioned supporting track, said truck 55 also having overhead tracks respectively associated with said supporting tracks and adapted to be brought into alignment with said first mentioned overhead track, means for supporting said truck for movement at 60 right angles to said tracks, and means for moving said truck.

8. A door arrangement for aircraft 65 hangars and the like, comprising a common supporting track adapted to receive a plurality of doors in end to end relation, a truck

located at one end of said track and movable at an angle thereto, and a plurality of substantially straight tracks on said truck disposed in parallel relation to one another one behind the other and adapted to be respectively brought into registry with said first mentioned track. 70
